ADOLPHE MINET AND HENRI LOUIS LÉONCE LUCAS, OF PARIS, FRANCE.

ELECTRIC FURNACE.

1,103,309.

Specification of Letters Patent. Patented July 14, 1914.

Application filed December 30, 1913. Serial No. 809,487.

To all whom it may concern:

Be it known that we, ADOLPHE MINET, of 4 Rue Théodore de Banville, and HENRI LOUIS LÉONCE LUCAS, of 73 Rue de Provence, both in the city of Paris, Republic of France, have invented Improvements in Electric Furnaces, of which the following is a full, clear, and exact description.

The object of the present invention is 10 to provide an electric furnace of the resistance type particularly suitable for the treatment of zinc ores.

The essentially novel feature of the improved furnace is the resistance by means of 15 which the required temperature is generated. This resistance is constituted by the combination of two resistances, viz., a principal resistance and a secondary resistance. The former generates the greater portion of the 20 heat set up by Joule effect and is constituted by a mass of granulated carbon which is maintained in shape by the pressure of the secondary resistance which rests upon it, so that the constancy of the values of 25 the current (voltage and amperage) during the whole reaction is insured. The secondary resistance, which is shunted relatively to the principal resistance, is constituted by pieces or blocks of material 30 which have a conductivity considerably less than that of the principal resistance so that only a small part of the current passes through it. These blocks are heated mainly by thermal conductivity and 35 distribute the heat to the retorts which are inclosed in suitably shaped cavities.

Another essential feature of the furnace is the electrodes each of which consists of a metal plate connected with the current 40 leading-in conductors, and a column of granulated carbon of high conductivity in contact, on the one hand, with said plates and, on the other hand, with the principal resistance. The effect of this arrangement 45 is to prevent such heating of the electrodes as would render them practically useless.

The invention is illustrated in the accompanying drawings wherein—

Figure 1 is a longitudinal section and 50 Fig. 2 a transverse section of the improved furnace.

a is the body of the furnace built of very refractory bricks covered by plates *b* of similar refractory material.

55 *c* are walls dividing the interior of the furnace, made of carbonaceous substances

sufficiently light that the pressure exerted by the walls shall not exceed 11,025 lbs. per 15.5 square inches. The interior of the furnace is of a size just sufficient to contain the heat generating resistances and the distillation retorts.

The resistances comprise two distinct elements, viz., a principal resistance *d* and a secondary resistance constituted by a 65 plurality of elements *d*¹, *d*², . . . *d*^s. The principal resistance *d* is constituted by a mass of granulated carbon of perfectly regular geometrical configuration having the form of a straight prism rectangular in 70 cross section. The constant pressure to which it is submitted owing to the fact that it supports the resistances *d*¹, *d*², . . . *d*^s and the retorts *e*¹, *e*², . . . *e*^s, prevents it from changing shape. Its conductivity is such 75 that it receives 90 per cent. of the current which passes through the furnace.

The resistances *d*¹, *d*², . . . *d*^s are constituted by prismatic blocks of rectangular shape in cross section which are hollowed out 80 and provided throughout their length with a channel within which the distillation retorts *e*¹, *e*², . . . *e*^s are received. These blocks are good conductors of heat but their electrical conductivity is ten times smaller than that of 85 the resistance *d*, so that only ten per cent. of the current passes through them. It is to be understood, however, that ninety and ten per cent. are not absolute values but are 90 values given by way of example only.

As only a small quantity of current passes through the resistances *d*¹, *d*² . . . *d*^s, they generate only a small amount of heat by Joule effect, but they transmit by thermal conductivity the heat generated by *d*; this 95 heat distributes itself throughout the mass of the resistances *d*¹, *d*² . . . *d*^s and, during the duration of the reaction, the temperatures distributed within the furnace remain 100 in perfect equilibrium.

The retorts *e*¹, *e*² are similar to those usually employed in the metallurgy of zinc and are provided with a condensation pocket *f* and a nozzle *g*. Current is led to the principal resistance *d* by means of electrodes 105 *h* each of which comprises a metal sheet *h* (usually of steel) to which the current leading-in conductor is attached. On this metal plate a column *i* of granulated carbon of very high conductivity rests. In practice 110 the conductivity of the latter is ten times greater than that of the carbon of *d*. Under

these conditions only a small amount of heat is generated in the column i by Joule effect. Owing to this arrangement, while the temperature of the resistance d reaches from 1500 to 1600 degrees when the furnace is in full reaction, that of the plates h does not exceed 300 to 400 degrees, and from this it follows that the electrodes are practically indestructible. It is also to be observed that the contacts between the plates h and the carbon granules constituting the columns i and between the granules of these columns and the granules of the principal resistance d , are insured solely by pressure, thus obviating the necessity of employing mechanical adjustments and preventing parasitic heating which is often the cause of rapid deterioration of adjustable electrodes.

In addition to the advantages above set forth (viz. continuous working and long duration, invariability of the constants of the current during the reaction, perfect adjustment and distribution of the temperature at different points within the furnace, indestructible electrodes and very high efficiency) the new furnace possesses numerous other advantages. For instance, owing to the fact that the interior capacity of the furnace is just sufficient to contain the resistances and the retorts, heat losses through the walls are reduced to a minimum and the thermal efficiency is very high. The retorts $e^1, e^2 \dots$ being surrounded by the blocks $d^1, d^2 \dots$ cannot become subjected to excessive heat and the heat is evenly distributed around their periphery. As they are supported throughout their length their thickness may be notably decreased, thus increasing their permeability to heat.

In the construction illustrated the resistance d is constituted by a single mass of carbon but when the furnace must have a

certain width, it might be constituted by a plurality of parallel masses. Similarly, the furnace may be constituted by a plurality of superposed floors.

Claims:

1. In an electric furnace, a principal resistance constituted by a mass of granulated carbon, and a secondary resistance constituted by blocks less conductive than the carbon, exerting a pressure on the principal resistance.
2. In an electric furnace, a principal resistance constituted by a mass of granulated carbon, a secondary resistance constituted by hollow blocks less conductive than the carbon, exerting a pressure on the principal resistance, and retorts arranged in the hollow blocks.
3. In an electric furnace, a principal resistance constituted by a mass of granulated carbon, a secondary resistance constituted by blocks less conductive than the carbon, exerting a pressure on the principal resistance and electrodes constituted by large granules of carbon and metal plates.
4. In an electric furnace, a principal resistance constituted by a mass of granulated carbon, a secondary resistance constituted by hollow blocks less conductive than the carbon, exerting a pressure on the principal resistance, retorts arranged in the hollow blocks, and electrodes constituted by large granules of carbon and metal plates.

The foregoing specification of our improvements in electric furnaces signed by us this 19th day of December, 1913.

ADOLPHE MINET.
HENRI LOUIS LÉONCE LUCAS.
